PAPER BAG HOLDER

Horace C. Harrison, Augusta, Ga.

Application December 5, 1941, Serial No. 421,839

4 Claims. (Cl. 211—51)

This invention relates generally to containers and more particularly to an improved paper bag holder.

One object of the invention is to provide a paper bag holder which is so constructed that paper bags held therein will be presented for easy and convenient withdrawal.

Another object of the invention is to provide a paper bag holder wherein means is employed for engagement with the upper end portion of the outermost paper bag for retaining the bags against accidental displacement.

A still further object of the invention is to provide a paper bag holder which is simple in construction and which may be mounted easily in an operative position.

Further objects of the invention, not mentioned hereinbefore, will become apparent during the course of the following description.

In the drawing:

Figure 1 is a front elevation of my improved bag holder, bags being shown in operative position therein in dotted lines and partly in elevation,

Figure 2 is a rear elevation of the device,

Figure 3 is a vertical sectional view on the line 3—3 of Figure 1,

Figure 4 is a horizontal sectional view on the line 4—4 of Figure 1, and

Figure 5 is a perspective view showing the device in operative position with a number of bags mounted therein.

In the drawing similar reference numerals will be employed to designate like parts throughout the views.

The numeral 1 indicates generally the body of my improved bag holder. The body 1 is preferably formed of sheet metal, of a suitable gage, and includes a rear wall 2, a bottom wall 3, which is disposed at right angles to the rear wall and a front wall or retaining lip 4. The upper margin of the front wall of the retaining lip 4 is bent upon itself, as shown at 5, to define a clamp, the purpose for which will be set forth in more detail hereinafter. As best seen in Figure 1, the side margins of the rear wall 2 are bent inwardly to define opposed guide tracks 6 and 7, said guide tracks extending throughout the length of said rear wall.

Extending about the lower end of the body is a bracing strip 8. The bracing strip has its forward portion clamped beneath the clamp defined by the overturned margin 5. The strip also extends inwardly to define side plates 9 and 10. Further, as best seen in Figures 2 and 4, the strip

8 has its opposite end portions extending along the inner surface of the back wall 2 and, as best seen in Figure 2, the end portions of said strip are threaded through pairs of vertically disposed spaced slots 11 which are formed in the wall 2 near its lower end and in the same horizontal plane with the margin 5. The free end portions of the strip 8 are caused to overlie the outer surface of the wall 2 between the slots of the pairs of slots 11, for anchoring the strip rigidly in position. Formed in the side plates 9 and 10 near their corresponding inner ends are openings 12, the purpose for which will be set forth hereinafter.

15 Slidably mounted in the tracks 6 and 7 of the rear wall 2 and against the front face thereof is an operating plate 13. The operating plate 13, like the body 1, is formed of sheet metal, and is of a width slightly less than that of the said body.

16 The operating plate is substantially rectangular in shape and is slidable vertically throughout the entire length of the wall 2. At its upper end and medially of its width the plate 13 is formed with an opening 14 for receiving a

20 hanger of any suitable design, a hook 15 being shown by way of example. Substantially medially of the width of the plate 13 and near the center thereof a portion of the plate 13 is struck rearwardly to define a hinge loop 16, said hinge loop

25 being of substantially triangular shape and having its apex 17 projected through a slot in the wall of the plate, said apex being turned down against the outer face of the plate so as to be out of the way. The hinge loop 16 is engageable

30 with the upper edge of the wall 2, when the operating plate is in its lowermost position, for defining a stop for limiting downward movement of said plate.

35 Swingly connected with the body is a follower 18. The follower 18 is of substantially inverted U shape and has side arms 19 which have their lower ends swingingly mounted in the openings 12. The bight portion, shown at 20, extends laterally and in spaced relation to the

40 upper edge of the wall 2 in a plane slightly above the horizontal plane of said wall. It will be noted that, inasmuch as the openings 12 are disposed near the corresponding inner ends of the side plates 9 and 10, the arms 19 of the

45 follower will be disposed obliquely with respect to the wall 2. Swingingly mounted in the hinge loop 16 and straddling the plate 13 is a connecting yoke 21. The yoke 21 includes legs 22 which terminate at their free ends with loops 55 23, said loops surrounding the bight portion 20

of the follower 18. It will now be understood that, when the plate 13 is shifted vertically on the wall 2, the yoke 21 will shift the follower 18 toward the wall 13. Conversely, when the plate 13 is lowered in the tracks of the wall 2, the legs 22 of the yoke 21 will shift the follower outwardly.

In use, a package of paper bags, indicated at 24, is placed with the lower ends of the bags in operative position in the compartment 25 which is defined by the rear wall 2, the bottom 3 and the front wall 4. In this position, the bags will extend upwardly with the innermost bag abutting the front faces of the plates 2 and 13. The follower will be disposed in spaced relation to the outer face of the outermost bag and the arms 19 and the legs 22 of said follower and the yoke 21, respectively, will confront the side edges of the bags for limiting said bags against lateral displacement. It should be understood that, when placing the bags in operative position, the plate 13 is in its lowermost position, so that the follower will be disposed with the bight portion thereof in maximum spaced relation to the walls 2 and 13, for permitting easy positioning of the bags.

After the bags have been placed in operative position, as hereinbefore described, the device is ready for use. When ready for use, the device is mounted with the hook 15 projecting through the opening 14. When supporting pressure is released from the body, said body will, by force of gravity, be shifted downwardly with respect to the operating plate 13, which, as stated, is held rigid. When the body shifts downwardly, the yoke 22 will shift the bight portion 20 of the follower 18 inwardly into engagement with a portion of the face of the outermost bag 24. When this is done, the bags will be effectively clamped between the follower and the outer faces of the walls 2 and 13. However, the bags may be readily removed by manually engaging portions of the bottoms thereof, displacing said bottom portions from the compartment 25, and pulling downwardly on the bags for disengaging the upper portion thereof from behind the bight portion of the follower 18.

Attention is particularly directed to the fact that, when a bag is removed, the body 2 will shift downwardly slightly, with respect to the plate 13, for causing the follower to move instantaneously into clamping position in engagement with the next succeeding bag. In this manner, the bags will be kept in proper position for withdrawal at all times and regardless of whether the device is filled to capacity or whether all but one or two of the bags have been removed.

As pointed out hereinbefore, the device is characterized by extreme simplicity in construction and maximum utility. Moreover, the device may be constructed cheaply to manufacture at low cost. When in use, the yoke and follower will cooperate with the side walls 9 and 10 and with the rear wall or plate 2 and the plate 13 for retaining the bags in proper operative position at all times.

It is thought that the construction and operation of my improved paper bag holder will now be clearly understood.

Having thus described the invention, what is claimed as new is:

1. A paper bag holder adapted to be suspended from a support and including a body for retaining a paper bag, an operating plate slidably mounted for vertical movement in a plane parallel to said body, a follower engageable with the paper bag for preventing accidental displacement of said paper bag, and means on the operating plate and operatively connected with the follower for retaining said follower in position in engagement with the paper bag, said paper bag being removable from the body and from behind said follower.

2. A paper bag holder adapted to be suspended from a support and including a body having walls defining a compartment, an operating plate slidably mounted for vertical movement on one of the walls, said compartment receiving lower end portions of a group of paper bags, a follower pivoted to the body, and means operatively connecting the follower with the operating plate, said body being movable with respect to the operating plate for shifting the follower and said means whereby said follower will be urged into engagement with a portion of one of the bags for retaining said bag against accidental displacement, said bag being removable from the compartment and from behind the follower.

3. A paper bag holder adapted to be suspended from a support and including a body having a rear wall, a bottom wall and a front wall, a strip extending about the body and defining side plates, an operating plate slidably mounted for vertical movement on the body, said body defining a compartment, a follower having a bight portion and having arms with their end portions swingingly connected with the side plates, said arms extending upwardly, a yoke operatively connected between the operating plate and the bight portion of the follower, and means swingingly connecting the yoke with the operating plate, said body being movable with respect to the operating plate for shifting the follower and yoke whereby the bight portion of the yoke will be positioned to overlie a portion of a paper bag for retaining the upper portion of said paper bag against displacement, the lower portion of said paper bag being contained in said compartment and being displaceable therefrom for permitting removal of the paper bag, the upper portion of said paper bag being displaceable from behind the bight portion of the yoke.

4. A paper bag holder adapted to be suspended from a support and including a body having a compartment, side plates for the body, a follower swingingly connected with the side plates, an operating plate slidably connected with the body, a yoke operatively connecting the operating plate with the follower, and means swingingly connecting the yoke with the operating plate, the body portion of the yoke being engageable with a portion of a paper bag for retaining the paper bag against displacement, said body being movable with respect to the operating plate as paper bags are removed from behind the bight portion of the follower whereby said follower will be retained in engagement with succeeding bags as preceding bags are removed.

HORACE C. HARRISON.
